UNITED STATES PATENT OFFICE.

WILLIAM T. BIRCH, OF CHICAGO, ILLINOIS.

PUMP-VALVE.

1,140,869.

Specification of Letters Patent. Patented May 25, 1915.

Original application filed January 29, 1913, Serial No. 702,958. Divided and this application filed February 7, 1914. Serial No. 817,157.

To all whom it may concern:

Be it known that I, WILLIAM T. BIRCH, a citizen of the United States, residing at Chicago, in the county of Cook and State of Illinois, have invented certain new and useful Improvements in Pump-Valves, of which the following is a specification.

My invention relates to improvements in pump valves and has for its general object 10 to provide a valve structure which shall have the combined advantages of few parts, simplicity and cheapness of construction, advantageous co-operation between its various elements and other practical benefits hereinafter to be made more clearly apparent.

Another object of my invention is to provide a double face double ring valve constructed so that when one face becomes inefficient by wear or injury, it can be turned 20 over and the reverse face used.

A further object of my invention is to utilize certain parts of the idle face of my double face valve for the purpose of cushioning the upstroke in order to prevent injury 25 to the valve structure and reduce the noise of operation to a minimum.

This application is a division of my patent for improvements in pump valves, Number 1,090,775 granted March 17th, 1914, in 30 which the specific form of ring and ring retaining means is claimed.

Other and further objects of my invention will become readily apparent to those skilled 35 in the art from a consideration of the following description of an embodiment thereof taken in conjunction with the accompanying drawings wherein—

Figure 1 is a vertical, central section through a valve constructed in accordance 40 with my invention. Fig. 2 is a transverse section taken on line 2—2 of Fig. 1. Fig. 3 is an enlarged, fragmentary section of parts of the structure shown in Fig. 1 and of the ring and body part before assembling; and 45 Fig. 4 is a similar section showing the rings in their final position prior to deflecting or spinning over the inner rib into its ring locking position.

In all the views, the same reference characters indicate similar parts.

Specifically 10 indicates the body part of the valve, of suitable metal, such as a casting of brass, having integral ring-engaging means or ribs upon both of its sides to secure packing rings thereto for operative as-

sociation with the face of the valve seat 11. I have shown the valve constructed with packing rings on each of its side faces so that after one set of rings has become defective by wear or injury the valve may be 60 reversed and the rings on the opposite side may be used. The body part is centrally perforated as at 12 to receive the stem 13, which extends from the hub 11' of the valve seat 11. The body part 10 of the valve has 65 extending laterally therefrom; and concentric with the said central perforation, a series of concentric ribs, 14, 15, 16 and 17 providing therebetween grooves 18—18' somewhat wider than the width of the packing 70 rings, to be carried by the body, at the seat engaging portions of said rings. The packing rings 19—19' are preferably composed of vulcanized or semi-vulcanized, rubber. The ring 19 is to be contained in the groove 75 18 between the ribs 14 and 15. The seating surface of the ring, that portion contained between the vertical edges 20 and 21, is somewhat narrower than the base portion 22, this base portion of the ring being tapered to the 80 vertical edge 21, it being substantially as wide as the groove 18. Fig. 3 shows the relative location of the parts of the double-face valve before the rings are placed in the 85 grooves 18—18' and Fig. 4 shows the location of the parts after the rings have been placed in the grooves and before the ribs 15—15 have been radially deflected into contact with the inclined portions 22 of the rings. For packing the stem 13, I provide a similar 90 but smaller packing ring 19' adapted to be contained in the groove 18' provided by the ribs 16 and 17. For the purpose of convenient construction, the wider base portion of this ring extends radially and outwardly 95 from its vertical edges. Both of these packing rings are made in the form substantially shown and vulcanized previous to placing them in the ring carrying portions of the valve body. After the rings have been 100 placed in their respective grooves, as shown in Fig. 4, the laterally extending annular ribs 15 and 16 are radially deflected, as shown in Fig. 1, by a process of rolling or spinning, causing the ribs to tightly engage 105 the enlarged tapered surfaces of the respective rings and to securely hold them in their proper positions in the body part of the valve without imposing any strain upon the body part of the valve tending to cause dis- 110

tortion thereof and causing the seating faces of the rings to be displaced from their normal horizontal plane. It will thus be seen that each of the packing rings is independently held in place by an integral part of the valve body. This construction has considerable advantage over prior structures wherein extraneous parts requiring screws, or the like, are employed to hold the rings in place as such arrangements are liable to disintegration and to become loosened and displaced by use.

The ribs 15 and 16 may be readily rolled in place for holding the rings in their proper positions much more quickly than a single screw could be inserted in the body part, and when these ribs have been deflected into their proper positions, for purpose described, they are there for all times and intimately secure and hold the rings in their places by intimate engagement with the entire circumference without possibility of disengagement. The double-face valve being employed, as shown in Fig. 1, the deflected rib 16, that may, at the time, be on the top surfaces of the valve, provides a convenient tapering guide for the valve-closing spring 23. The upper end of the spring 23 engages under the curled-over edge 24 of the cup 25 which is secured by screw-threaded engagement to the upper end of the stem and by means of the nut 26. The spring 23 acts in the usual fashion to return the valve to its seat and yieldingly 35 to permit the opening of the valve. The idle packing ring 19' surrounding the valve stem on the upper side of the valve cushions the blow against the head 25 when the valve body is thrown to extreme upper position. It is therefore apparent that the construction providing a double-face, double-ring valve in this particular form not only attains the desired feature of reversibility but also the advantages of a cushioned, noiseless and efficient valve.

Some of the advantages of my device over prior structures will become readily apparent to persons skilled in the art from the foregoing description. The integral means 50 of intimately securing the packing ring at every point along and adjacent to its circumferential surface, after the ring has been

inserted, is of great structural and operative value. It is further clearly advantageous for the reason there is no strain imposed upon the body part of the packing-ring-carrying body to cause it to become warped or distorted; therefore, the contacting faces of the outer and inner packing rings will remain always in the same horizontal plane. The perfect axial alignment of the spring, maintained by the laterally projecting, deflected rib, inclosing the smaller packing ring, in coöperation with the guiding nut 25, prevents shifting 65 of the spring to either side of the central axis which would tend to produce an undesirable clutching effect between the center bore of the valve body 10 and the stem 13, increasing friction between the parts and 70 frequently causing "sticking" of the valve. The application of spring pressure so near the axial center is also beneficial.

Having described my invention, what I claim is:—

75

1. A two face valve body; a plurality of rings, carried on each face and integral means carried by the valve body for clamping the rings thereto.

2. In a device of the character described, 80 a double face reversible valve, comprising a valve body, having a central stem receiving aperture, a valve seat, a stem projecting therefrom to receive and guide said valve body, two concentric packing rings 85 secured to each side face of said valve body, one ring on each face approximately surrounding said stem, a head on the upper end of said stem to receive a valve seating spring; a spring engaging said head, and 90 encompassing the rib inclosing the smaller idle packing ring, whereby said spring is held concentrically with the stem and said smaller packing ring is brought into contact with the fixed spring head, to cushion 95 and render noiseless the blow due to the extreme movement of said valve body.

In testimony whereof I hereunto set my hand in the presence of two subscribing witnesses.

WILLIAM T. BIRCH.

In the presence of—

FORÉE BAIN,
MARY F. ALLEN.
